UNITED STATES PATENT OFFICE.

ARTHUR W. GAVITT, OF CHICAGO, ILLINOIS, ASSIGNOR TO A. STEIN & COMPANY, OF CHICAGO, ILLINOIS, A CORPORATION.

FOLDING MACHINE FOR FABRIC BLANKS.

1,420,480.

Specification of Letters Patent. Patented June 20, 1922.

Application filed July 26, 1920. Serial No. 399,073.

To all whom it may concern:

Be it known that I, ARTHUR W. GAVITT, a citizen of the United States, and a resident of Chicago, in the county of Cook and State 5 of Illinois, have invented certain new and useful Improvements in Folding Machines for Fabric Blanks, of which I do declare the following to be a full, clear, and exact description, reference being had to the accompanying drawings, forming a part of this 10 specification.

The present invention has relation to that class of folding machines more particularly designed for folding the edges of fabric 15 blanks from which such articles as garter pads, collars, cuffs and the like are to be formed, and the invention consists in the features of novelty hereinafter described, illustrated in the accompanying drawings 20 and particularly pointed out in the claims at the end of this specification.

In the accompanying drawings, my invention is shown as applied to a folding machine set forth in an application for Letters Patent 25 filed in the United States Patent Office by Alexander D. Elliott January 22, 1920, Sr. No. 353,323, in which machine the fabric blanks to be folded are adapted to be acted upon by a series of groups or units of 30 folder blades and dies or templets, the groups of folder blades being carried by a revolute table that is moved by a step-by-step motion so as to bring the folder blades successively beneath the dies or templets that cooperate 35 therewith in folding the edges of the blanks. In the machine set forth in said Elliott application, the fabric blanks, after their edges had been folded and pressed, were removed from the revolute table by means of an arm 40 provided with pins adapted to engage the fabric blank and move the same from the machine into a suitable receptacle.

The object of my present invention is to provide a simple and effective mechanism 45 whereby the fabric blanks after they have been folded can be conveniently aggregated and moved to such position that they can be readily formed into bundles or packages.

Referring to the drawings, Fig. 1 is a 50 view in side elevation of a folding machine, such as set forth in said Elliott application, having my invention applied thereto. Figure 2 is an enlarged view, partly in vertical section and partly in elevation, showing a portion 55 of the revolute table with the folder blades carried thereby, showing a por-

tion of the vertically movable frame beneath the revolute table and showing the folded blank receiver above the movable table. Figure 3 is a view similar to Fig. 2 but 60 showing the parts in different position. Figure 4 is an enlarged detail plan view of one of the groups of folder blades mounted upon the revolute table. Figure 5 is an enlarged detail view, partly in elevation and partly 65 in vertical section, showing the manner in which the folded fabric blanks are moved into the folded blank receiver. Figure 6 is a detail view in vertical section on line 6—6 of Fig. 2. Figure 7 is an enlarged detail view in cross section on line 7—7 of Fig. 1. Figure 8 is a view in section on line 8—8 of Fig. 9. Figure 9 is a view in vertical section on the line 9—9 of Fig. 2.

The main frame of the machine is similar 75 in construction to that set forth in the above mentioned Elliott application, and comprises corner posts A, the upper portions of which are connected together by the skeleton frames or cross plates A' and A'', the frame 80 A'' serving, as in said Elliott machine, to support the templets (not shown) and the presser devices that cooperate with the units or groups of folder blades carried by the revolute table 14 that is fixed to the vertical 85 shaft 15.

In my present machine, as in said Elliott machine, there is mounted beneath the revolute table A'' that carries the groups or units of folder blades, a vertically movable 90 table A' having depending cams a³ that are acted upon by rollers a⁴ carried by a shifting plate or bar A⁴ that is moved in the direction of the arrow Fig. 1 by a cam B upon a vertical cam shaft B'. The table A' 95 is provided with a plurality of groups of upstanding cam fingers a⁵ adapted when the table A' is raised, to shift the depending bars or arms a⁶ whereby the folder blades a⁷ will be moved back and forth to fold the 100 edges of the fabric blanks. As these features form no part of my present invention and are fully set forth in said Elliott application, I do not deem it necessary to describe the details thereof further herein.

The machine illustrated is more particularly designed for the folding of the blanks from which garter pads are to be made, these blanks being of a general triangular outline, and it will be understood that as the table 110 A'' carrying the groups or units of folder blades revolves with a step-by-step motion

in front of the operator, a fabric blank will be delivered to each group or unit of folder blades and the blanks will be successively carried first beneath the die or dies that co-operate with the folder blades in folding the edges of the fabric blanks, and, after the edges are folded, the blanks are advanced by the revoluble table beneath the presser mechanism shown at A⁷ in Fig. 1 of the drawings. After the fabric blanks have been thus folded and pressed, they will be in readiness to be removed from the revoluble table by my improved mechanism next to be described.

15 Through the revoluble table 14 and through each of the revoluble supports a⁸ associated with each group or unit of folder blades pass the rods 30 that have fixed to their upper ends a plate 31, on which the 20 fabric blank to be folded will be placed. These rods 30 are encircled by coiled springs 32 the upper ends of which bear against the revoluble table 14, while their lower ends bear upon a plate or bar 33 that is fixed to 25 the lower ends of the rods 30. The springs 32 thus serve to hold the rods 30 and the plate 31 in the normally retracted position shown in Fig. 2 of the drawings. Upon 30 the top of the vertically movable table A³ (see Figs. 1 and 2) are mounted upright bars or posts 35 adapted to contact with the bar or plate 33 when the table A³ is raised.

After a fabric blank has been folded and pressed by being moved (as in the Elliott machine above mentioned) successively beneath the dies or templets and the pressing mechanism A⁷ (see Fig. 1), it will next be moved beneath the folded blank receiver designated as D, the position of the parts then being as illustrated in Fig. 2 of the drawings. The folded blank receiver D preferably comprises a cage or receptacle formed of a series of rods 40 the upper ends of which are connected to a plate 41 fixed to 40 the top of the cross plate A² above an opening formed therein, this plate 41 having an opening corresponding in outline to the form of the folder blanks W. Preferably, the upper ends of the rods 40 are formed 45 with vertical seats to receive guide pins 42 that constitute an extension of the folded blank receiver, as clearly shown in Figs. 1 and 2 of the drawings. The top plate A¹ of the main frame will be open at a point 50 above the rods 42. The lower ends of the rods 40 have fixed thereto a plate 43, this plate being preferably of the shape shown in Fig. 7 of the drawings. To the plate 43 beneath the lower end of each of the rods 55 40 is attached, as by set screws 45, a channel-shaped bracket 46 (see Fig. 8) in which is pivoted, as at 47, a dog or catch 48 that normally gravitates to the position shown in Fig. 9 of the drawings. Each pawl 48 is 60 formed with a slot through which passes a 65

pin 49, the ends of this pin 49 being mounted in the side walls of the bracket 46.

From the foregoing description it will be seen that when a fabric blank has had its edges folded and pressed and has been 70 brought beneath the folded blank receiver D, a vertical movement is imparted to the table A³, the posts 35 will contact with the plate 33 and will lift the plunger rods 30 and the plate 31 from the position shown in Fig. 75 2 to the position shown in Fig. 3 of the drawings, thereby lifting the folded fabric blank past the pivoted dogs or catches 48 until the blank is within the receiver D, as 80 illustrated in Fig. 3 of the drawings. As the table A³ recedes, the dogs 48, the free ends of which have been forced backward by the upward movement of the fabric blank, will 85 resume their normal position and will serve to engage the edges of the fabric blank and prevent its downward movement with the plate 31; it being understood that the dogs 48, when in normal position, will permit the plate 31 to pass. In this way, the fabric 90 blanks, after they have been folded and pressed, will be successively added to the stack of blanks within the receptacle D and gradually the blanks will pass from between the rods 40 upward into the space between the supplemental rods 42, from which they 95 may be readily lifted by the operator from time to time and formed into bundles.

While I have described what I regard as the preferred embodiment of my invention, I wish it understood that the details of construction above set out may be varied without departure from the scope of the invention and features of the invention may be employed without its adoption as an entirety. 105

Having thus described my invention, what I claim as new and desire to secure by Letters Patent is:—

1. In a machine of the character described, the combination with suitable means for 110 folding the fabric blanks, of a support for the fabric blanks to be folded, means for moving said support vertically to lift the folded fabric blanks, a blank receiver open at its bottom to admit the folded fabric 115 blanks, and dogging mechanism to hold said fabric blanks within the receiver after they have been delivered thereto.

2. In a machine of the character described, the combination with suitable means for 120 folding the fabric blanks, of a support for the fabric blanks to be folded, means for moving said support vertically to lift the folded fabric blanks, a blank receiver open at its bottom to admit the folded fabric 125 blanks, and movable catches at the bottom of said receiver for holding the fabric blanks within the receiver after they have been delivered thereto.

3. In a machine of the character described, 130

the combination with suitable means for folding the fabric blanks, of a support for the fabric blanks to be folded, means for moving said support vertically to lift the 5 folded fabric blanks, and pivoted dogs at the bottom of said receiver for holding said fabric blanks within the receiver after they have been delivered thereto.

4. In a machine of the character described, 10 the combination with suitable means for folding fabric blanks, of a support for the fabric blanks to be folded, means for moving said support vertically to lift the folded fabric blanks, a blank receiver open at its 15 bottom to admit the folded fabric blanks and open at its opposite end for the removal of the fabric blanks, and means for preventing the fabric blanks from passing from the bottom of the receiver after they have 20 been delivered thereto.

5. In a machine of the character described, the combination with suitable means for folding the fabric blanks, of a support for the fabric blanks to be folded, means for 25 moving said support vertically to lift the folded fabric blanks, a blank receiver open at its bottom to admit the folded fabric blanks and open at its top for discharge of the fabric blanks, said receiver comprising 30 vertical rods, and means for preventing the dropping of the fabric blanks from the bottom of said receiver after they have been delivered thereto.

6. In a machine of the character described, 35 the combination with suitable means for folding the fabric blanks, of a support for the fabric blanks to be folded, means for moving said support vertically to lift the folded fabric blanks, a blank receiver open 40 at its bottom to admit the folded fabric blanks and open at its top for the discharge of said blanks, a series of brackets arranged beneath said receiver, and a series of pivoted dogs or catches carried by said brackets and 45 adapted to prevent the dropping of said fabric blanks from said receiver.

7. In a machine of the character described the combination with suitable means for folding the fabric blanks, of a support for 50 the fabric blanks to be folded, said support being arranged adjacent said means for folding the fabric blanks, a vertically movable member arranged to lift said support, a blank receiver open at its bottom to admit 55 the folded fabric blanks, and means to prevent said fabric blanks from dropping from said receiver after they have been delivered thereto.

8. In a machine of the character described, 60 the combination with suitable means for folding the fabric blanks, of a support for the fabric blanks to be folded, spring mechanism for forcing said support normally downward, a movable member for moving 65 said support vertically to lift the folded

fabric blanks, a blank receiver open at its bottom to admit the folded fabric blanks, and means for preventing the fabric blanks from dropping from said receiver after they have been delivered thereto.

9. In a machine of the character described, the combination with suitable means for folding the fabric blanks, of a support for the fabric blanks to be folded, rods connected to and depending from said support, spring 75 mechanism for forcing said support normally downward, a movable bar for raising said support vertically to lift the folded fabric blanks, a blank receiver open at its bottom to admit the folded fabric blanks, 80 and means to prevent said fabric blanks from dropping from said receiver after they have been delivered thereto.

10. In a machine of the character described, the combination with suitable means 85 for folding the fabric blanks, means for lifting the folded blanks, a blank receiver open at its bottom to receive said folded blanks, and means for holding said blanks within the receiver after they have been delivered 90 thereto.

11. In a machine of the character described, the combination with a support for the blanks to be folded, of means for folding the blanks on said support, a receiver for 95 the folded blanks disposed above said support, and means for lifting said support to deposit the folded blanks in said receiver.

12. In a machine of the character described, the combination with suitable means 100 for folding the fabric blanks, of a movable support for the fabric blanks to be folded, a receiver for the folded blanks, and means mounted on and movable with said support for lifting the folded blanks from the support into the receiver when the support is brought into position beneath said receiver.

13. In a machine of the character described, the combination with a plurality of movable supports for the blanks to be folded, 110 of means for folding the blank on each of said supports, a stationary receiver for the folded blanks, means for successively moving said supports opposite said receiver, and means for conducting the folded blank from 115 each support to said receiver when the support is opposite said receiver.

14. In a machine of the character described, the combination with a plurality of movable supports for the blanks to be folded, 120 of means for folding the blanks on each of said supports, a stationary receiver for the folded blanks, means for successively moving said supports opposite said receiver, and means mounted on and movable with each 125 of said supports for conducting the folded blank thereon to said receiver when the support is opposite said receiver.
